WAVE PUMP

Norman M. Lewis, Olton, Tex.

Application August 19, 1946, Serial No. 691,506

3 Claims. (Cl. 103—69)

1

This invention pertains to marine equipment and more particularly to wave motors, as they are generally termed.

It is an object of this invention to provide a new and improved wave motor that will avoid one or more of the disadvantages and limitations of the prior art.

Another object of the present invention is to provide a new and improved wave motor that will be capable of pumping water to a relatively high level by directly using the power of waves of the sea.

Other objects will become apparent as the invention is more fully set forth.

For a better understanding of the invention reference is made to the appended drawings and the following description wherein a particular form of the invention is illustrated by way of example, while the scope of the invention is more emphatically presented in the claims.

In the construction indicated in the drawings:

Figure 1 is a plan view of a wave pump embodying this invention.

Figure 2 is a side elevation of Figure 1.

Figure 3 is a sectional elevation through the pump unit, and

Figure 4 is a sectional view taken along line 4—4 of Figure 3.

Similar reference characters refer to similar parts throughout the drawings.

The structure in this particular form is relatively simple. It consists of a wave lifting float 10 adjustably attached to the end portion of a lever arm 11 pivoted on a fulcrum shaft 12 situated a sufficient length away to afford considerable leverage at its short arm 13. The short arm 13 operates a pump 15. A slot 16 in the arm 13 receives a connection 14 attached to the hollow cylinder 17, and permits adjustment thereon. The fulcrum shaft 12 is journaled in a supporting post 27 that is solidly or rigidly built into the floor bottom of the sea. The pump consists of a hollow cylinder 17 having its upper end open, while its bottom is closed and fitted with a liftable check valve 18. The cylinder 17 reciprocates in a housing 19 which is likewise cylindrically hollow. The cylinder 17 operates through the open end of the lower portion 20 of the housing. The upper portion 21 of the housing 19 is tapered and leads to a small orifice 22, which is also closed by a liftable check valve 24. A conducting pipe 25 of restricted diameter leads from the orifice to some extraneous location where a reservoir tank 26 is preferably installed on the shore. The purpose of the pump is to force water from the sea

2

through itself, to the reservoir and fill the latter. The operation of the device is simple. The depression of the waves at the proper location, allows the float to drop under the action of gravity and carry the long lever arm 11 with it. As it drops it raises the cylinder 17 with the water entrapped in it.

The entrapment of the water is caused by the closing of the valve 18 as the water in the cylinder 17 presses down on it during lifting. The raising of the cylinder 17 reduces the space in the housing and forces the entrapped water up through it and past the check valve 24. From there it passes through the piping 25 to the reservoir 26. When the waves raise the float, the cylinder 17 is lowered and its check valve 18 opens and more water enters to fill the cylinder 17 and casing 19. At the same time the valve 24 closes and keeps water in the piping 25 within it, so it cannot empty backwards. The float 10 is made adjustable on the lever arm 11 so it can vary its effect on the cylinder 17 and pump working parts. The leverage of the arm 11 is greater than the short arm 13, so that its effect is magnified and the water may be raised above the level of the sea actuating the waves that operate the float.

Since the waves are operating continuously, they tend to make the pump operate to accumulate a large amount of pumped water. This water may be used in any manner that suits the owners of the equipment. Since only the wave power is utilized, it is unnecessary to provide for the variations of the wave level and tide, as the waves have an underwater effect that will act upon the equipment even though the level changes. Since the water is entirely enclosed in the system, it does not matter materially whether it becomes submerged or not.

While but one general form of the invention is shown in the drawings and described in the specifications, it is not desired to limit this application for patent to this particular form or in any other way otherwise than limited by the scope thereof, as it is appreciated that other forms of construction could be made that would use the same principles and come within the scope of the appended claims.

Having thus described the invention, what is claimed is:

50. 1. A wave motor comprising in combination, a rigid support for placement in water having a substantial wave action movement therein, a lever having a plurality of fulcrum holes for adjustably positioning the lever on said support and providing a relatively long arm on one side

and a relatively short arm having an elongated slot at the other side, an adjustable float mountable on said long arm, an adjustable connection on the short arm, a hollow cylinder adjustably attached to the elongated slot in the short arm by said connection and operated thereby, a housing for the cylinder to operate in and carry water entrained therein and raise it to a higher level than that of the operating waves, and a conductor for carrying off said pumped water to an extraneous location.

2. A wave motor comprising in combination, a rigid support for placement in water having a substantial wave action movement therein, a lever having a plurality of fulcrum holes for adjustably positioning the lever on said support and providing a relatively long arm on one side and a relatively short arm having an elongated slot at the other side, an adjustable float mountable on said long arm, an adjustable connection on the short arm, a hollow cylinder adjustably attached to the elongated slot in the short arm by said connection and operated thereby, a housing for the cylinder to operate in and carry water entrained therein and raise it to a higher level than that of the operating waves, a conductor for carrying off said pumped water to an extraneous location, and valves for facilitating the entrainment of the flow of water in and out of the cylinder and housing automatically with the action of the waves operating said lever.

3. A wave motor comprising in combination, a rigid support for placement in water having a substantial wave action movement therein, a lever having a plurality of fulcrum holes for adjustably positioning the lever on said support and

providing a relatively long arm on one side and a relatively short arm having an elongated slot at the other side, an adjustable float mountable on said long arm, an adjustable connection on the short arm, a hollow cylinder adjustably attached to the elongated slot in the short arm by said connection and operated thereby, a housing for the cylinder to operate in and carry water entrained therein and raise it to a higher level than that of the operating waves, and a conductor for carrying of said pumped water to an extraneous location, valves for facilitating the entrainment of the flow of water in and out of the cylinder and housing automatically with the action of the waves operating said lever, and piping connecting the housing with the reservoir for providing a closed system between the sea and the reservoir, said housing being restricted to reduce the amount of water during said reciprocation and increase its rate of flow through the piping.
